[57] ABSTRACT

An upright floor cleaner comprising a base, an upper housing and an operation handle, the upper housing and handle being pivotally mounted relative to the base, between an upright at rest condition and a lowered operation condition, the handle in the upright condition projecting upwardly above the housing and curving through an arc to a generally horizontal orientation, and in the operation condition extending diagonally rearwardly-upwardly and then curving through the arc to a generally vertical downward orientation.

UPRIGHT FLOOR CLEANER

BACKGROUND OF THE INVENTION

This invention relates to upright carpet vacuum floor cleaners, commonly also called upright vacuum cleaners.

Upright cleaners of many different styles and shapes have been known heretofore. Typical cleaners have a base that includes floor engaging roller brushes and a motor, an upper housing as for receiving the vacuum bag, and a handle to pull and push the cleaner over a floor surface.

The housing and handle are typically pivotal relative to the base to move between an upright storage condition and a rearwardly tilted operational condition. These cleaners are normally pushed and pulled repeatedly in a series of repetitive movements over the floor surface for cleaning purposes. This is done by the operator gripping the handle and moving the cleaner back and forth. In so doing, the operator's hand is at an awkward angle, which causes undue fatigue in the hand, wrist, arm, and shoulder of the operator.

SUMMARY OF THE INVENTION

The present invention provides a unique upright floor cleaner and handle assembly which has ergonomically desirable characteristics. As usual, the handle and upper housing of the cleaner are pivoted on the base to move between an upright storage condition and a rearwardly tilted operational condition. The handle in the upright condition extends vertically and slightly forwardly, then curves through an arc of about 90 degrees to a generally horizontal orientation. In the tilted operational condition, the handle slopes rearwardly upward, then up slightly, then through the 90-degree arc to a generally rearwardly downward orientation. The handle configuration is superior to the prior art, substantially reducing fatigue to the operator. The handle is preferably of molded polymeric material. On the front of the polymeric handle is an integral upwardly oriented, hose receiving hook. On the rear of the handle are upwardly and downwardly oriented, electric cord-receiving hooks.

These and other features, advantages and objects of the present invention will be further understood and appreciated by those skilled in the art by reference to the following specification, claims and appended drawings.

BRIEF DESCRIPTION OF THE DRAWINGS

- FIG. 1 is a perspective view of the novel cleaner;
- FIG. 2 is a front elevational view of the cleaner;
- FIG. 3 is a rear elevational view of the cleaner;
- FIG. 4 is a side elevational sectional view of the cleaner;
- FIG. 5 is a front elevational sectional view of the cleaner;
- FIG. 6 is a side elevational view of the cleaner showing it in three positions;
- FIG. 7 is a top plan view of the bag housing;
- FIG. 8 is a bottom view of the cleaner;
- FIG. 9 is a top view of the cleaner;
- FIG. 10 is an enlarged bottom view of the cleaner showing the underside cover panel cut away;
- FIG. 11 is a front elevational view of the bag housing, partially sectioned;
- FIG. 12 is a side elevational view of the bag housing, partially cut away;
- FIG. 13 is a side elevational view of the handle;
- FIG. 14 is a rear elevational view of the handle;
- FIG. 15 is a front elevational view of the rear handle; and

FIGS. 16A-16H are sectional views taken at various places through the handle in FIG. 15.

DETAILED DESCRIPTION OF PREFERRED EMBODIMENT

Referring now specifically to the drawings, the novel cleaner 10 has three major components or subassemblies, namely base subassembly 12, filter bag subassembly 14, and handle subassembly 16.

Base subassembly 12 comprises a base housing 20 which may be formed of various materials, but is preferably of roto-molded polymeric material. At the rear of this housing are rotationally mounted a pair of rear wheels 22. Midway between the rear and the front of the housing but offset more toward the front of the housing is a roller 24 (FIG. 4). Roller 24 is adjustable vertically by knob 26, to be moved vertically around pivot point 28 for controlling the degree of engagement of cleaning brush 30 with the floor surface to be cleaned. Cleaning brush 30 comprises an elongated cylindrical element extending across the front of the base (FIGS. 8 and 10) and mounted in end bearings 32. It has an elongated cylindrical hub 34 and radially projecting bristles 36 in a double helical pattern. The helical pattern of the bristles is in two opposite helical directions from the two opposite ends, the two patterns meeting at the area adjacent inlet nozzle 38 of duct 40. Typically the brush rotates in a direction such that the bristles move downwardly at the front of the brush and upwardly at the rear of the brush. These two portions of helical pattern brushes cooperate with a special reflector ledge 42 in a manner to be described hereinafter. Brush 30 is rotated by belts 48 on pulley 50 at the end of the brush, the belts being driven by pulley hub 52 on electric motor 54 retained within a motor receiving chamber of housing 20. Beneath motor 54 and some other portions of housing 20 is a removable underside cover panel 21. Brush 30 is exposed through an elongated opening in the panel.

Housing 20 defines a generally semi-cylindrical, elongated brush receiving cavity 58 (FIG. 4) that extends transversely of the housing and receives brush 30. It is open on the bottom to allow peripheral brush bristle engagement with the carpeted floor surface to be cleaned. Extending transversely across the housing at the rear of brush receiving cavity 58 is a special particle reflection and air tunnel ledge 42 (FIGS. 4, 8, and 10), which cooperates with brush 30 and suction nozzle 38. The particle reflection and air tunnel ledge has an upwardly concave, elongated configuration (see FIG. 4) that cooperates with the brush bristles to create air tunnel-like air flow along its length, i.e., generally parallel to the brush axis, toward nozzle 38. Nozzle 38 is located between the two ends of brush 30, typically offset more toward one end than the other. Two portions 42a and 42b of elongated reflection ledge 42 meet adjacent nozzle 38. Inverted reflector ledge 42, which is about 0.030 inch from the periphery of the brush bristles, preferably slopes upwardly from both ends thereof (FIG. 10) to an apex in front of nozzle 38. In the embodiment depicted, portion 42a of ledge 42 is considerably shorter than portion 42b extending from the opposite end, so as to meet in front of nozzle 38. The concave surface of inverted ledge 42 also slopes rearwardly upwardly from its forward apex as depicted in FIG. 4. Its position close to the brush bristles causes this reflector surface to be engaged by rising sand, pea gravel, ice melt, and salt pellet particles propelled by brush 30 as the brush rotates rearwardly during operation of the cleaner. These particles are reflected into the concave space to be advanced by the axial air flow along the reflection ledge. It has been found that the use of the special particle reflector

and air tunnel ledge, in combination with the closely adjacent helical brush characteristics, causes even larger particles to progressively bounce off the reflective ledge, each bounce bringing the particles closer to nozzle 38 so that ultimately the particles are drawn through nozzle 38 and duct 40 toward a dirt retaining receptacle in bag housing 14.

Upright dirt retention housing 14, preferably formed of roto-molded polymeric material such as polyethylene, has handle subassembly 16 attached to it by fasteners 70 (FIG. 4). Housing 14 and handle 16 are pivotally attached at pivots 72 to base 12, to enable the housing and handle to be pivoted between an upright storage condition and a plurality of lowered upwardly-rearwardly sloping conditions, the most common of which is shown as the intermediate position in phantom lines in FIG. 6. If necessary, housing 14 and handle 16 can be lowered to the maximum amount depicted adjacent the floor surface in FIG. 6. Bag housing 14 (FIG. 4) has a peripherally enclosing inner wall 74 of significant thickness, defining a bag receiving chamber 76 therein. The housing also includes an outer wall 78 of significant thickness integrally joined at the top with inner wall 74 and spaced from the inner wall over its length, including at the bottom of the two walls, to define a space 80 therebetween. The outer surface of outer wall 78 is smooth as shown in FIG. 1, preferably having a front surface, a rear surface, and two side surfaces, all of which are generally planar. The inner wall 74 has an undulating characteristic, preferably generally sinusoidal along its two side walls, its front wall, and its back wall as depicted in FIG. 7. The corners are preferably diagonally positioned. These undulations define a plurality of vertically elongated recesses 84 and inwardly projecting, intermediate, vertically elongated protrusions 86. Placement of a dirt bag inside housing 14 is achieved by opening a pivotal cover 88 (FIG. 4) about frontal pivot point 90 to open the housing top for access to space 76. Recesses 84 provide excellent airflow passages adjacent the outer side walls of the dirt bag (not shown) placed in space 76. At the bottom of space 76 is the bag housing vacuum outlet 92 (FIG. 7), which communicates through a lateral passage 93 (FIG. 5) with vacuum motor and pump unit 94 (FIG. 5) to create a negative pressure, i.e., partial vacuum, around the bag exterior inside chamber 76. The porous dirt bag causes a lower negative pressure inside the bag. At the top of housing 14, extending through cover 88, is a tube 98 which serves as the inlet tube for dirt-laden air flow drawn from brush chamber 58 through nozzle 38, duct 40, hose 102 (FIG. 3), duct 104, and hose 106, to tube 98 and hence to chamber 76. It has also been determined that the undulation configuration of inner wall 74 allows easy removal of a filled dirt bag from chamber 76, because of minimal friction between wall 74 and the bag.

Base assembly 12 has a chamber 73 which is specially configured to receive and retain the vacuum motor and pump 94, as can be seen in FIGS. 4 and 5. Its bottom and side walls are curved to match the motor and pump so that no added fasteners need be used to retain them in position. The top is closed by a cover plate 75.

Handle 16 has a unique configuration and preferably is formed of molded polymer material. The handle extends upwardly above housing 14 when the cleaner is in the upright storage condition depicted in FIGS. 4 and 6. The handle extends upwardly above housing 14 in a vertical orientation, curves slightly forwardly near the top of the handle, then through an approximate 90 degree arc, and extends horizontally to the rear. The arcuate portion and horizontal extension constitute a hand grip zone 16'. The span of this arcuate portion is at least as large as the width

of an adult human hand, i.e., about three inches or greater, to function effectively and comfortably. The diameter of the handle at the hand grip zone is at least about one inch, and is preferably about one and one-half inches. When the cleaner is lowered to the normal operating condition shown as the intermediate position in FIG. 6, handle 16 then extends diagonally upwardly-rearwardly, then slightly upwardly to blend into the 90° arcuate portion, and then extends diagonally downwardly rearwardly. This sloped downwardly-rearwardly orientation has been found to be 5 ergonomically advantageous to accommodate the normal hand position of an operator during the constant push-and-pull movement of the cleaner across the floor. If the cleaner housing and handle need to be lowered further, e.g., to 10 positions between the two phantom line depictions in FIG. 6, the curved arcuate portion still constitutes an ergonomically correct position as a hand grip for the hand of the operator. Consequently, the operator will experience considerably less fatigue. The cross-sectional configuration of 15 handle 16 is preferably substantially circular in the hand grip region, and can gradually converge into a more oval configuration as shown by the sectional views 16a-16h. Optionally, the topmost portion can be slightly oval in configuration with a larger vertical axis than transverse axis.

20 Integrally formed into the front of the upper portion of handle 16 is an upstanding hose hook 110 (FIG. 13) for draping of the vacuum hose 106 thereover as shown in FIG. 6. On the rear side of handle 16, near the upper end thereof, is an upstanding hook 114A cooperable with a lower, downwardly projecting hook 114, to serve as a cord windup zone for the electrical cord. An integral carrying handle portion 118 projecting rearwardly of handle 16 includes an upstanding hook 112 to retain a standard fitting 116. This fitting may 25 be used for attachment to the hose to clean corner areas or the like.

During operation, a bag is placed in space 76 by pivotally 30 opening cover 88 to provide an open top to space 76, after which the cover is pivoted closed to seal around the bag upper surface. Power is then applied to the cleaner to actuate the vacuum motor and pump unit 94, as well as electric 35 motor 54 which drives brush 30. The operator then moves the bag housing and handle from the upright storage position to a rearward diagonal position, such as the middle position shown in FIG. 6, and pushes and pulls the cleaner back and forth across the floor surface to be cleaned. The operator's 40 hand can slide readily from the rearmost, substantially straight portion of the handle to and from the arcuate portion, if desired. Rotating brush 30, when encountering difficult-to-retrieve particles such as sand, salt pellets, and 45 the like, will auger the particles from both ends of brush 30 toward nozzle 38 by bouncing the particles repeatedly off inverted ledge 42, the particles advancing longitudinally 50 along the upwardly sloped concave ledge to nozzle 38, assisted by the air flow through the concave ledge space, and hence to duct 40, from whence it moves ultimately to tube 98 into the dirt bag. Negative pressure is created in the dirt bag by the vacuum motor drawing air from the undulation recesses 84 for efficient drawing of the air through the porous bag wall which filters out the dirt. A secondary filter 55 120 is preferably placed over vacuum outlet 92 at the bottom of space 76 (FIG. 4). If desired, a third filter can be placed upstream of vacuum pump 94. When the dirt bag is full, as indicated by a yellow light which can be used to signal a full or a clogged bag, the unit is shut down, cover 88 is pivotally 60 opened, and the filled dirt bag is removed, this removal being readily done because of minimal friction of the bag on the protrusions 86.

The above description is considered that of the preferred embodiment only. Modifications of the invention will occur to those skilled in the art and to those who make or use the invention. Therefore, it is understood that the embodiment shown in the drawings and described above is merely for illustrative purposes and not intended to limit the scope of the invention, which is defined by the following claims as interpreted according to the principles of patent law, including the doctrine of equivalents.

The invention claimed is:

1. An upright floor cleaner comprising:

a base, an upper housing and an operation handle, said upper housing and said handle being pivotally mounted relative to said base, between an upright at rest condition and a lowered operation condition;

said handle in said upright condition projecting upwardly above said housing and curving through an arc to a generally horizontal orientation, and in said operation condition extending diagonally rearwardly-upward and then curving through said arc to a diagonally rearwardly downward orientation;

wherein said handle in said upright condition projects upwardly, it then projects at a small angle forwardly, and then curves through said arc to said generally horizontal orientation.

2. The upright floor cleaner in claim 1 wherein said arc has a span greater than the width of a hand of an adult operator.

3. The upright floor cleaner in claim 1 wherein said arc has a span of at least about three inches, to accommodate the hand of an adult operator.

4. The upright floor cleaner in claim 3 wherein said handle has a generally round hand grip zone which includes said arc and is at least one inch in diameter.

5. The upright floor cleaner in claim 4 wherein said hand grip zone is about one and one-half inch in diameter.

6. The upright floor cleaner in claim 1 wherein said handle at said arc and said generally horizontal orientation is substantially circular in cross section.

7. The upright floor cleaner in claim 1 wherein said handle at said arc and said generally horizontal orientation is substantially circular in cross section.

8. The upright floor cleaner in claim 1 wherein said handle is of molded polymer and includes an upwardly oriented hose hook for receiving a hose.

9. The upright floor cleaner in claim 8 wherein said hose hook is on the front of said handle, and said handle also has upwardly and downwardly extending cord hooks.

10. The upright floor cleaner in claim 9 wherein said cord hooks are on the rear of said handle.

11. An upright floor cleaner comprising:

a base, an upper housing and an operation handle, said upper housing and said handle being pivotally mounted relative to said base, between an upright at rest condition and a lowered operation condition;

said handle in said upright condition projecting upwardly above said housing and curving through an arc to a generally horizontal orientation, and in said operation

condition extending diagonally rearwardly-upward and then curving through said arc to a diagonally rearwardly downward orientation;

wherein said handle is of molded polymer and includes an upwardly oriented hose hook for receiving a hose.

12. The upright floor cleaner in claim 11 wherein said arc has a span greater than the width of a hand of an adult operator.

13. The upright floor cleaner in claim 11 wherein said arc has a span of at least about three inches, to accommodate the hand of an adult operator.

14. The upright floor cleaner in claim 13 wherein said handle has a generally round hand grip zone which includes said arc and is at least one inch in diameter.

15. The upright floor cleaner in claim 14 wherein said hand grip zone is about one and one-half inch in diameter.

16. The upright floor cleaner in claim 11 wherein said handle at said arc and said generally horizontal orientation is substantially circular in cross section.

17. The upright floor cleaner in claim 11 wherein said hose hook is on the front of said handle, and said handle also has upwardly and downwardly extending cord hooks.

18. The upright floor cleaner in claim 17 wherein said cord hooks are on the rear of said handle.

19. An upright floor cleaner comprising:

a base, an upper housing and an operation handle, said upper housing and said handle being pivotally mounted relative to said base, between an upright at rest condition and a lowered operation condition;

said handle in said upright condition projecting upwardly above said housing and curving through an arc to a generally horizontal orientation, and in said operation condition extending diagonally rearwardly-upward and then curving through said arc to a diagonally rearwardly downward orientation;

wherein said handle includes an upwardly oriented hose hook for receiving a hose.

20. The upright floor cleaner in claim 19 wherein said arc has a span greater than the width of a hand of an adult operator.

21. The upright floor cleaner in claim 19 wherein said arc has a span of at least about three inches, to accommodate the hand of an adult operator.

22. The upright floor cleaner in claim 19 wherein said handle at said arc and said generally horizontal orientation is substantially circular in cross section.

23. The upright floor cleaner in claim 19 wherein said handle hook is on the front of said handle, and said handle also has upwardly and downwardly extending cord hooks.

24. The upright floor cleaner in claim 23 wherein said cord hooks are on the rear of said handle.

25. The upright floor cleaner in claim 19 wherein said handle has a generally round hand grip zone which includes said arc and is at least one inch in diameter.

26. The upright floor cleaner in claim 25 wherein said hand grip zone is about one and one-half inch in diameter.
